(57) **CLAIM**

The ornamental design for a light fixture, as shown and described.

DESCRIPTION

FIG. 1 is a perspective view of the light fixture;
FIG. 2 is a bottom plan view of the light fixture of FIG. 1;
FIG. 3 is a top plan view of the light fixture of FIG. 1;
FIG. 4 is a right-side elevation of the light fixture of FIG. 1, the left-side elevation view being a mirror image thereof; and,
FIG. 5 is a front elevation of the light fixture of FIG. 1, the rear elevation being a mirror image thereof.
The phantom lines are provided for illustrative purposes only
and form no part of the claimed design.
